UNITED STATES PATENT OFFICE.

GEORGE HENRY WHEARY, OF RACINE, WISCONSIN.

TRUNK-HINGE FIXTURE.

1,118,983.

Specification of Letters Patent.

Patented Dec. 1, 1914.

Application filed June 18, 1914. Serial No. 845,777.

To all whom it may concern:

Be it known that I, GEORGE HENRY WHEARY, a citizen of the United States, and resident of Racine, in the county of Racine and State of Wisconsin, have invented new and useful Improvements in Trunk-Hinge Fixtures, of which the following is a description, reference being had to the accompanying drawings, which are a part 10 of this specification.

The invention relates to improvements in trunk hinge fixtures, and more particularly to fixtures for wardrobe trunks.

Many of the wardrobe trunks now on the market rest upon one end and are divided vertically, medially into two hinged together sections, the upper end of one of said sections being open and provided with a hinged end top cover. These end covers 15 have heretofore been secured to the sections by separate hinges and locking fixtures. As thus secured, the connections in many ways lack the strength and rigidity desired in the manufacture of trunks.

20 It is one of the objects of the present invention to overcome the before mentioned objectionable features and combine the top cover hinge and the upper section hinge with the side fixture of the trunk, and thereby provide a hinge fixture which possesses greater strength and rigidity than the same parts used independently.

A further object of the invention is to provide a trunk hinge fixture which is adapted to bind the adjacent sections and cover of a trunk of the before mentioned type in order to resist torsional strains or working of the parts with relation to each other, and to bind the parts, when in closed 30 position, into a rigid structure.

A further object of the invention is to provide a trunk hinge fixture which is so constructed as to automatically lock the top cover and the side sections together when 35 said parts are swung to closed position.

A further object of the invention is to provide a trunk hinge fixture which is of very simple construction, is well adapted for the purpose desired and which may 40 be manufactured at a minimum cost.

With the above and other objects in view, the invention consists of the improved trunk hinge fixture, and its parts and combinations as set forth in the claims, and all 45 equivalents thereof.

In the accompanying drawing in which the same reference characters indicate the same parts in all of the views: Figure 1 is a side view of the improved trunk fixture shown mounted on a trunk portion, the 60 view also indicating by dotted lines one of the parts swung toward open position; Fig. 2 is a view of the inner side of the fixture; Fig. 3 is a top view of the fixture, parts broken away and other parts in section to 65 show interior construction; Fig. 4 is an edge view of the fixture; and Fig. 5 is a rear view on a smaller scale of a trunk provided with the improved fixture.

Referring to the drawing the numeral 8 70 indicates the body section, 9 the wardrobe section hinged thereto along its rear vertical edge, and 10 the top cover of a wardrobe trunk of the type for which the improved trunk hinge fixture is particularly adapted 75 for use in connection therewith. The improved fixture 11, attached to the rear upper portion of the trunk at the point of junction of the two sections and the cover and extending over the upper end portions 80 of the trunk, comprises the main or body section member 12, the lower or wardrobe section member 13 and the top cover member 14, which are attached respectively to the body section, the wardrobe section and 85 the top cover of said trunk.

The fixture is stamped from sheet metal and when assembled is of approximately rectangular shape and is bent transversely medially of its length into L shape to form 90 the top portion 15 and the side portion 16. While the transverse bend is of rounded form as indicated by the numeral 17, to conform to the rounded edge portion of the trunk, it is obvious that the corner may 95 be formed with a right angle bend if desired.

The rectangular piece of material is divided medially, vertically to form the body member 12, and the other half portion is divided horizontally to form the top cover member 14 and the wardrobe section member 13 before described. The upper horizontally extending and abutting edges of the body member and the top cover are provided with edgewise overlapping eyed portions 18 through which extends a hinge pintle member 19 to hingedly connect the two parts together. The inner abutting edges of the wardrobe section member and 105 110

the lower portion of the body section member are also provided with edgewise overlapping eyed portions 20 through which extends a hinge pintle member 21 to hingedly connect these parts together.

5 The vertically extending portion of the body member 12 of the fixture at its front edge is provided with a forwardly projecting tongue 22 which is adapted to enter the recess 23 of the top cover member 14 when the parts are in closed position. The top cover member is also provided with a downwardly projecting tongue 24 which enters a recess 25 formed in the upper edge portion of the wardrobe section member. The recesses of the respective members are formed by embossing or bulging outwardly a semi-circular portion of the fixture to form a reinforcing half circular rib 26, the center of which is the point of junction of the inner corner edges of the members of the fitting. The projecting tongues are also in circumferential alinement with the semi-annular rib, so that when the parts are in 20 closed or locked position the rib portions of the different members will be in circumferential alinement with each other.

In order to provide a smooth exterior surface of the adjacent rib portions the projecting tongues are offset inwardly the thickness 30 of the material the plates or members are formed of. These offset portions form shoulders 27 which abut against the edges of the rib portions forming the rib recesses.

35 It will be noted that in view of the short radius or arc of swing of the projecting tongue 24 that a portion of the rib forming the recess 25 is cut away on its outer side to form a side opening 28 to permit the movement of said tongue, and also in order to preserve the ornate contour of the semi-annular rib, the tongue 24 is provided with an offset rib portion 29 which corresponds in shape to the part cut away from the recess 40 portion 25, and when the parts are in closed position, fills said side opening.

The fixture is provided with perforations 30 to receive rivets or other securing means 31 for securing the fixture to the trunk portions.

From the foregoing description it will be seen that the trunk fixture is of simple construction and combines a plurality of hinges and locking fittings into one fixture.

55 What I claim as my invention is:

1. A trunk fixture, consisting of a three-part member having a locking engagement with each other, two of the parts being hingedly connected to the third part.

60 2. A trunk fixture, consisting of a three-part member having a tongue and recess engagement with each other, two of the parts being hingedly connected to the third part.

3. A trunk fixture, comprising a body member having an upper portion extending

at an angle with relation thereto, a cover member having a portion extending at an angle with relation thereto which is hingedly connected to the angular portion of the body member, and a wardrobe member hinged to 75 the body member and abutting edgewise against an edge portion of the cover member, all of said members having a tongue and recess locking engagement with each other.

4. A trunk fixture, comprising an angular body member having a tongue projecting from one edge thereof, an angular cover member having its angular portion hingedly connected to the angular portion of the body member and adapted into edge-abutting engagement therewith, said cover member provided with a downwardly-extending tongue and with a recessed portion into which the tongue of the body member extends, and a 80 wardrobe section member hinged to the lower portion of the body member and adapted to edgewise engage the edge portions of the other members and having a recessed portion into which the downwardly 85 extending tongue of the cover member extends.

5. A trunk fixture, comprising an angular body member having a tongue projecting from one edge thereof, an angular cover member having the angular portion hingedly connected to the angular portion of the body member and adapted into edge-abutting engagement therewith, said cover member provided with a downwardly extending tongue 95 and with a recessed portion into which the tongue of the body member extends, and a wardrobe section member hinged to the lower portion of the body member and adapted to edgewise engage the edge portions of the other members and having a recessed portion into which the downwardly 100 extending tongue of the cover member extends, the tongue and recessed portions of the respective members being in the form of 105 a semi-circular rib of which parts are all formed on each member.

6. A trunk fixture, comprising an angular body member having a tongue projecting from one end of a portion of a semi-circular rib formed on the side portion of the member, an angular cover member having its upper portion hinged to the upper portion of the body member, the lower edge 115 portion of the cover member terminating on a line in a plane co-incident with the axis of the circular rib, said cover member having a portion of a semi-circular rib formed thereon which is in circumferential alinement with the rib portion of the body member and forming a recess to receive the tongue of the body member, the lower edge portion of said cover member provided with a downwardly 120 extending tongue in circumferential aline- 125

ment with the rib, and a wardrobe section member hinged to the lower portion of the body member and adapted to edgewise engage the edges of the body member and the 5 top member, and having a portion of a semi-annular rib formed thereon which forms a recess to receive the depending tongue of the cover member, said wardrobe section mem-

ber rib being in circumferential alinement with the rib parts of the other members. 10

In testimony whereof, I affix my signature, in presence of two witnesses.

GEORGE HENRY WHEARY.
